US0D1038826S

(12) **United States Design Patent** (10) **Patent No.:** **US D1,038,826 S**
(45) **Date of Patent:** **** Aug. 13, 2024**

(54) **STRAP ANCHOR**

(71) Applicant: **5.11, Inc.**, Manteca, CA (US)

(72) Inventor: **Matthew Noble**, Manteca, CA (US)

(73) Assignee: **5.11, Inc.**, Manteca, CA (US)

(**) Term: **15 Years**

(21) Appl. No.: **29/774,681**

(22) Filed: **Mar. 18, 2021**

Related U.S. Application Data

(62) Division of application No. 29/685,267, filed on Mar. 27, 2019, now Pat. No. Des. 913,843.

(57) **CLAIM**

The ornamental design for a strap anchor, as shown and described.

DESCRIPTION

FIG. 1 is a perspective view of a strap anchor, showing my new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken lines in the drawings represent portions of the strap anchor and form no part of the claimed design.

1 Claim, 5 Drawing Sheets
